Des. 221,889

Patented Sept. 14, 1971

221,889

LUBRICATOR RESERVOIR OR SIMILAR ARTICLE

Donald G. Gruett, Manitowoc, Wis., assignor to
Oil-Rite Corporation, Manitowoc, Wis.

Filed Apr. 15, 1970, Ser. No. 22,448

Term of patent 14 years

Int. Cl. D15—99

U.S. Cl. D46—1

FIG. 1

FIG. 4

FIG. 2

FIG. 5

FIG. 3

FIG. 6

FIG. 1 is an elevational view showing the design for a lubricator reservoir or similar article;

FIG. 2 is a top plan view of the reservoir;

FIG. 3 is a bottom plan view showing the design;

FIG. 4 is an elevational view of another embodiment of the lubricator reservoir;

FIG. 5 is a top plan view of the reservoir of FIG. 4, and

FIG. 6 is a bottom plan view of the reservoir of FIG. 4. I claim:

The ornamental design for a lubricator reservoir or similar article, substantially as shown and described.
